CLAIM

The ornamental design for swing sport wrist training aid, as shown and described.

DESCRIPTION

FIG. 1 is a perspective view of the swing sport wrist training aid shown in an unfastened position;

FIG. 2 is another perspective view of the swing sport wrist training aid shown in an fastened position;

FIG. 3 is a top plan view of the swing sport wrist training aid showing my new design;

FIG. 4 is a left side view of FIG. 3;

FIG. 5 is a right side view of FIG. 3;

FIG. 6 is a front view of FIG. 3; and,

FIG. 7 is a rear view of FIG. 3.

In the drawings, the broken lines depict unclaimed subject matter only and form no part of the claimed design.
